REINFORCED SPRING ASSEMBLY FOR
UPHOLSTERYLouis A. Suekoff, Wilmette, Ill., assignor to
Nachman Spring-Filled Corporation, Chicago,
Ill., a corporation of Illinois

Application April 24, 1931. Serial No. 532,467

3 Claims. (Cl. 155—179)

This invention relates to improvements in spring assemblies for upholstery of the type wherein the springs of the structure are maintained in predetermined relative positions by 5 means of fabric webs secured to or engaged with the end coils of springs.

The main object of the present invention is to provide means whereby the flexible top and bottom walls of spring assemblies of the type above mentioned are yieldingly maintained substantially taut, thus to prevent crowding together and overlapping of the end coils of the component springs as hereinafter more fully explained.

In the accompanying drawing illustrating suitable embodiments of the invention:

Fig. 1 is a plan section of spring assembly constructed in accordance with the invention.

Fig. 2 is a similar view showing a modified form of construction of the same.

Fig. 3 is a fragmentary plan view of the same illustrating another form of embodiment of the invention.

The invention herein illustrated is embodied in the type of spring assemblies wherein the end coils of the springs 1, which are usually of the hour-glass type, are engaged in flat fabric pockets formed between two sheets of fabric secured together by sets of parallel stitch-chains 2 and 3 extending transversely to each other to define substantially square areas of diameter substantially equal to that of the end coils of the springs 1. The said end coils of the latter are inserted into the pockets formed between said fabric sheets through the openings 4. This type of structure is shown in various prior patents and reference is had particularly to United States Patents Nos. 1,755,713, 1,755,714 and 1,755,715, all issued April 22, 1930.

In practice, the spring assemblies of the general class above-named, which includes other specific types of construction than is herein shown or is shown in the above-mentioned patents, are covered with suitable padding material which is also disposed peripherally about the same and they are then crowded into the open end of a cover fabric which includes the usual top and bottom walls and boxing or peripheral walls.

In thus crowding the spring assembly and padding into the cover fabric, the springs 1 are crowded toward each other and frequently into overlapping relation to each other so that the cover fabric is not fully distended laterally.

Aside from the crowding above referred to during manufacture of the cushions, this action results, to an appreciable extent, in the use of the

cushions, from persons disposing themselves upon the front edge portions thereof and either remaining so disposed or sliding rearwardly. In both cases, the springs are apt to be crowded away from the front edge of the cushion. 80

The use of border frames of wire secured to the peripheral edge portions of top and bottom fabric walls has been resorted to as a means for maintaining the said fabrics sufficiently taut to prevent the said crowding, but to provide 85 border frames possessing sufficient resistance to bowing or distortion to produce this result has necessitated the use of very heavy wire which, in turn, is objectionable in that it prevents the front edge portions of the cushion from conforming 70 itself to the shape of the thighs resting upon the same and, in the case of cushions of width to accommodate more than one person, a very heavy occupant depresses the front rail of the border frame to deprive the adjacent occupant of the support of the front edge portion 75 of the cushion. These border frames also cause the front edge portion of the cover fabric of the cushion to be subjected to undue wear.

Hence, the object of the present invention is 80 to provide very light and effective means for maintaining the fabric top and bottom walls of cushions sufficiently taut to prevent the aforesaid crowding without subjecting the person or persons seated thereon to any discomfort and 85 without causing any part of the cover fabric to be subjected to undue wear.

To this end the invention consists in securing to the fabrics engaged with the end coils of the springs 1 and supported by or supporting the latter, resilient bow-spring members 5 of relatively light gauge spring wire. As shown in Fig. 1, the spring members 5 may be plural and, as shown in Fig. 2, may consist of a single or unitary member 5^a.

The same members 5 or 5^a, as the case may be, are secured to the fabrics aforesaid by stitching 6 and 6^a, or any suitable equivalent thereof, which preferably penetrates the fabric at points along the stitch-chains 2 and 3, respectively, in 100 structures of the specific type shown in order that said stitching 6 or 6^a may not interfere with the insertion of the end coils of the springs in the aforesaid flat pockets.

The members 5 and 5^a may be generally defined as bow-spring members which will yield to lateral pressures against cushion edges and to load upon the cushions but will spring back to normal condition.

Preferably these spring members 5 and 5^a or 110

their equivalents, will extend to points coincident with the outer edges of the marginal springs of the structure at points midway of the ends of the respective rows of said marginal springs, 5 the shape of the said spring members being varied to suit that of the cushion or certain areas thereof, it being understood, of course, that a plurality of said spring members may be disposed throughout the length of a bench-cushion or the like.

10 The invention may be embodied in many different forms of spring members which may, as shown in Fig. 3, be composed of crimped or corrugated spring wire 7 for greater elasticity, if desired.

15 The said bow-spring members 5, 5^a, or 7, as the case may be, act upon the central or body portion of a square or substantially square cushion, it being relatively unimportant to maintain the corner portions of the latter taut because 20 they are less subject to crowding and distortion than said middle or central portions.

Obviously, in the case of larger cushions wherein a plurality of seat areas are incorporated into a unitary structure, the bow-spring members used will be disposed in the relation to 25 each other best adapted to effect the desired result.

30 In the instances illustrated, the bow-spring members are secured to the inner opposed faces of the top and bottom fabric sheets. While this is preferable as well as most practical in the case of the specific type of structure herein illustrated, it is, in cases of other types of fabric spring assemblies, necessary to secure the said 35 bow-spring members to the outer surfaces of the top and bottom fabrics. In such instances, the said members are covered by the padding material so that they cannot be felt by occupants of the cushions.

40 I claim as my invention:

45 1. A spring assembly comprising top and bottom fabric walls, a group of upholstery springs interposed between said top and bottom walls, fabric means associated with said top and bottom walls and engaged with said springs and with 50 said walls and constituting the sole means for maintaining the springs of said group normally in

predetermined relative positions, and flexible, resilient wire means secured to one of the said walls and extending, in part, to the front and rear edges thereof, and, in part, over springs of the group from front to rear edges thereof, for maintaining said wall taut throughout the area bordered by said means, the latter being sufficiently resilient to prevent interference thereof with the normal load responsive action of the said springs of the said group over which said means extend.

2. A spring assembly comprising top and bottom fabric walls, a group of upholstery springs interposed between said top and bottom walls, fabric means associated with said top and bottom walls and engaged with said springs and with said walls and constituting the sole means for maintaining the springs of said group normally in pre-determined relative positions and flexible, resilient arcuate wire means secured to one of the said fabric walls and extending in part, to the front and rear edges thereof, and in part, over springs of the group from front to rear edges thereof, for maintaining said walls taut throughout the area bordered by said means, the latter being sufficiently resilient to prevent interference thereof with the normal load responsive action of the said springs of said group over which said means extend.

3. A spring assembly comprising top and bottom fabric walls, a group of upholstery springs interposed between said top and bottom walls, fabric means associated with said top and bottom walls and engaged with said springs and with said walls and constituting the sole means for maintaining the springs of said group normally in pre-determined relative positions, and flexible, resilient, substantially circular wire means secured to one of the said walls and extending in part, to the front and rear edges thereof, and, in part, over springs of the group from front to rear edges thereof for maintaining said wall taut throughout the area bordered by said means, the latter being sufficiently resilient to prevent interference thereof with the normal load responsive action of the said springs of said group over which said means extend.
